STREET SIGN

Filed Dec. 14, 1935

UNITED STATES PATENT OFFICE

2,076,081

STREET SIGN

Armin H. Gottlieb, New York, N. Y.

Application December 14, 1935, Serial No. 54,400

1 Claim. (Cl. 40—132)

This invention relates to new and useful improvements in a street sign.

The invention has for an object the construction of a street sign which is adapted to be illuminated from the interior thereof.

More particularly, the invention contemplates the provision of a hollow casing adapted to be attached at one end upon a street sign post and having an open opposed end, and window openings in the front and rear walls, and translucent signs supported on the inner faces of the front and rear walls viewable through the window openings. With this arrangement it is possible to illuminate the interior of the casing for the purpose of illuminating signs.

Still further the invention proposes the provision of a cover plate for closing the open end of the casing and simultaneously serving to hold the transparent signs in position.

As a further object it is proposed to associate resilient means with each of the sign elements by which they are partially extended when the cover is removed from position.

Another object of the invention is the construction of a device as mentioned which is simple and durable and which may be manufactured and sold at a reasonable cost.

For further comprehension of the invention, and of the objects and advantages thereof, reference will be had to the following description and accompanying drawing, and to the appended claim in which the various novel features of the invention is more particularly set forth.

In the accompanying drawing forming a material part of this disclosure:—

Fig. 1 is a perspective view of a street post with a street sign constructed according to this invention.

Fig. 2 is a fragmentary perspective view of a portion of the street sign, illustrated with the cover plate removed and the transparent signs partially extended.

Fig. 3 is a sectional view taken on the line 3—3 of Fig. 2.

Fig. 4 is a horizontal sectional view taken on the line 4—4 of Fig. 2.

Fig. 5 is a horizontal sectional view taken on the line 5—5 of Fig. 1.

Fig. 6 is a fragmentary enlarged sectional view taken on the line 6—6 of Fig. 2.

Fig. 7 is a fragmentary view similar to a portion of Fig. 2 but illustrating a modification of the invention.

In Fig. 1 a conventional street post 10 is illustrated upon which there is mounted a bracket 11

to which the street signs 12 are attached. Each of these street signs comprise a hollow casing 12' adapted to be attached at one end upon the bracket 11 and having an opposed open end 13. This hollow casing is also formed at the front and rear walls with window openings 14, 14^a, etc., through which translucent signs 15, 15^a etc., are viewable. These signs are supported upon the inner faces of the front and rear walls.

Within the casing lamps 16 are supported, which are adapted to illuminate the translucent signs. A cover plate 17 is for the purpose of closing the open end of the hollow casing.

The hollow casing 12' has a semi-cylindrical top portion 12^a, the ends of which are formed with openings 12^b through which the heat generated by the lamps may escape. The signs 15^a, 15^b etc., are supported by horizontal T-shaped tracks 19 mounted upon the casing 12' and arranged longitudinally of the window openings 14, 14^a etc. These tracks 18 are open at the ends so that the signs 15, 15^a, etc., may be slipped from their positions. The L-shaped tracks 18 are fastened to the top portion 12^a which in turn is mounted on the casing 12' (see Fig. 3). The cover 17 has a bottom tongue 17^a which may engage into the bottom end of the side opening 13 (see particularly Figs. 2 and 4). At the top the cover plate 17 is provided with a lock 20 by which it may be locked to the top edge of the opening 13. Springs 21, 21^a, etc., are mounted on the casing 12', on the inner wall thereof and are adapted to partially extend the signs 15, 15^a, etc., as clearly shown in Fig. 2. When the cover 17 is forced into position the signs 15, 15^a etc., will be forced inwards and the springs 21, 21^a, etc., will be flattened out against the inner end wall of the casing. These signs 15, 15^a etc. are formed of translucent glass having transparent areas for the numbers, letters etc. In Fig. 7 a modification of the invention is shown in which the casing 12'' is formed with window openings 22 arranged on the bottom thereof. These window openings are covered with translucent material 23. The object of these openings is to permit some of the light from the lamps to be directed downwards to illuminate the street immediately below the signs.

While I have illustrated and described the preferred embodiment of my invention, it is to be understood that I do not limit myself to the precise construction herein disclosed and the right is reserved to all changes and modifications coming within the scope of the invention as defined in the appended claim.

Having thus described my invention, what I

claim as new, and desire to secure by United States Letters Patent is:—

In a street sign, a hollow casing adapted to be attached at one end upon a street sign post and having an open opposed end and window openings in the front and rear walls, translucent signs supported upon the inner faces of the front and rear wall and viewable through said window openings, lamps supported within said casing to illuminate said signs, and a cover plate for closing said open end of the casing, longitudinal

tracks being secured upon the inner walls of the casing and serve to support said translucent signs, said tracks having open ends at the open end of the casing so that the translucent signs may be removed from the casing and means for ejecting the said signs at different distances when said cover plate is removed, comprising springs attached on the casing and acting against the inner ends of the signs. 5
